CLAIM

The ornamental design for a compact tank, as shown and described.

DESCRIPTION

FIG. 1 is a top perspective view of a compact tank showing our new design;

FIG. 2 is a left side view of the compact tank illustrated in FIG. 1;

FIG. 3 is a right side view of the compact tank illustrated in FIG. 1;

FIG. 4 is a front view of the compact tank illustrated in FIG. 1;

FIG. 5 is a back side view of the compact tank illustrated in FIG. 1;

FIG. 6 is a top view of the compact tank illustrated in FIG. 1; and,

FIG. 7 is a bottom view of the compact tank illustrated in FIG. 1.

The broken lines immediately adjacent the shaded areas represent the bounds of the claimed design while all other broken lines are included for the purpose of illustrating portions of the compact tank; the broken lines form no part of the claimed design.
